UNITED STATES PATENT OFFICE.

HERBERT A. AUSTIN, OF WORCESTER, MASSACHUSETTS.

FASTENING LOOP.

Application filed March 25, 1926. Serial No. 97,411.

This invention relates to a loop for use in fastening and holding various articles but particularly articles of clothing such as sanitary napkins.

5 The principal object of the invention is to provide for this purpose a loop of very simple character in which the clamping bar will be held in clamping position by friction so that it cannot be removed therefrom except by the exertion of a direct force against it and cannot be removed by pulling on the garment which is attached to it.

Other objects and advantages of the invention will appear hereinafter.

15 Reference is to be had to the accompanying drawings in which:

Fig. 1 is an elevation showing a preferred form of the loop as employed for attaching a sanitary napkin to another garment;

20 Fig. 2 is a sectional view of the same on the line 2—2 of Fig. 1;

Fig. 3 is a view similar to Fig. 1 showing the loop substantially in clamping position without the articles to be fastened;

25 Fig. 4 is a sectional view of the same on the line 4—4 of Fig. 3;

Fig. 5 is a view of the piece of wire which constitutes the frame of the loop;

30 Fig. 6 is a view similar to Fig. 3 of a modification but showing the clamping bar in raised or inoperative position; and

Fig. 7 is an edge view of the same.

35 Loops having the same general appearance and used for similar purposes are now on the market, but in these loops the clamping bar is loosely mounted on the frame so that it is free to move from the position shown in Fig. 3 to that shown in Fig. 6 and does not offer any resistance against 40 such motion, whereby they are likely to become loose and fail to perform their function.

45 Referring to the form shown in Figs. 1 to 5, the frame consists of a single piece of wire 10 having two ends 11 which diverge from each other in the condition shown in this figure. The sides of the loop are formed of a horizontal bottom wire and the two ends 12, and these sides are parallel. 50 To complete the frame itself a tube 13 is provided, receiving the two ends 12 and permitting them to move along it a little as the ends 11 of the frame are moved back and forth. This provides a certain amount 55 of flexibility and the set of the wire frame

normally holds these ends in the position shown in Fig. 5 if no force is applied.

The clamping bar 14 consists of a flat piece of sheet metal, preferably with a center projection at the bottom which is adapted to engage over the bottom straight bar of the frame to clamp a piece of cloth thereto. As stated above, this clamping action is relied upon in the devices now on the market and there is no resistance except 65 the friction of the bar 14 on the bottom horizontal bar of the frame 10 to hold the parts in clamping position.

With my invention, however, the passages which are formed through the ends of the 70 clamping bar 14 as shown in Fig. 4 are just large enough so that when the clamping bar is down in clamping position as shown in Fig. 1 the ends 11 of the frame bear against the outer sides of these passages 15 at the top 75 with a certain amount of friction. If no force is applied directly to move the clamping bar upwardly, this friction is enough to hold it and if force is applied the friction grows stronger if the clamping bar is moved 80 slightly as it has to overcome the resiliency of the wire frame and the natural divergence of the ends 11.

This clamping bar, when moved to the top 85 as indicated in Fig. 6, will stay in that position on account of that friction until it is moved therefrom instead of dropping down, interfering with the threading of the garment through the loop.

90 The principal object of my invention, however, lies in the fact that when a piece of tape, gauze or other cloth 16 is passed over the clamping bar and down behind the frame it will stay there, as the clamping bar is frictionally held in position at its ends. Any 95 pulling on the tape 16 will not dislodge it or lessen the clamping effect.

This loop of course, is intended to be connected to another garment 17 by doubling it over the top of the frame and sewing it 100 as is well understood in this art.

The frame shown in Figs. 6 and 7 works in exactly the same way, except that the ends of the wire frame are flattened at 18 so as to provide projections 19 at their outer surfaces 105 bearing even more efficiently on the passages 15 of the clamping bar 14 to hold it in clamping position.

Although I have illustrated and described only two forms of the invention, I am aware 110

of the fact that other modifications can be made therein by any person skilled in the art without departing from the scope of the invention as expressed in the claim. Therefore I do not wish to be limited to all the details of construction herein described, but what I do claim is:

As an article of manufacture, a fastening loop of wire having parallel sides and ends 10 that are diverging, the ends of the wire being located in one of said sides and spaced apart, a tube enclosing said ends of the wire and of a length shorter than the normal dis-

tance between said ends at the wider side, and a sliding clamping bar parallel with 15 said sides and having passages at its ends for the ends of the wire frame, said passages engaging the ends of the frame frictionally in all positions of the clamping bar, for the purpose described, said wire being flattened 20 to provide opposite projections to hold the clamping bar in clamping position.

In testimony whereof I have hereunto affixed my signature.

HERBERT A. AUSTIN.
